LOOM

Samuel P. Parker, La Grange, Ga., assignor to
 Callaway Mills Company, La Grange, Ga., a
 corporation of Georgia

Application February 1, 1950, Serial No. 141,680

5 Claims. (Cl. 139—71)

1

This invention relates to control means for looms for weaving terry fabrics, such as are used for towels, wash cloths, etc., and is concerned more particularly with a novel dobby mechanism especially adapted for use with a terry loom supplied with pile yarns of at least two colors and producing a fabric with pile areas made up of a ground formed of loops of one color and figures formed of loops of another color. The new dobby may be used in place of a Jacquard mechanism for controlling a loom in the weaving of the terry fabric described and, since a dobby loom can be operated at a substantially higher speed than a Jacquard loom, the use of the new dobby results in a considerable reduction in cost. In addition, the preparation of the pattern chain employed with the dobby is less expensive than punching a set of Jacquard cards and portions of the chain may be reassembled to produce a new chain, when a pattern change is necessary.

An example of a fabric of the kind referred to above is one used in making hotel towels woven on the face with a center stripe of one color, usually white, on which the name of the hotel appears in letters of a different color, such as red. In such a fabric, the lettering appears on both faces of the fabric on a background of a contrasting color and, since the arrangement of the colors on the back is the reverse of that on the face, the fabric is commonly referred to as a reversible center name fabric. In the weaving of such a fabric by means of a Jacquard mechanism, a set of cards must be prepared for each name to be woven and regular production of towels for a number of different customer's thus involves making a considerable investment in cards.

The present invention is directed to the production of a dobby mechanism, which may be used with a terry loom in the production of reversible center name fabrics and others of the same general construction. The new dobby is actuated by the usual chain, but is of such construction that, in terry weaving, the chain need have only one bar for each three picks forming a beat-up, whereas the chain employed with an ordinary dobby includes a bar for each pick. The pegging of the bars of a chain for the new dobby is thus much simpler than the preparation of a chain for an ordinary dobby and, since the bars are detachable and groups of bars representing a single letter may be reassembled for the production of different names, reversible center name fabrics may be made for many customers by the use of the new dobby without a large in-

2

vestment in bars or substantial expense in changing over from one pattern to another.

For a better understanding of the invention, reference may be made to the accompanying drawings, in which

Fig. 1 is a view in elevation of one form of the new dobby mounted on a loom, together with a dobby jack and a harness frame controlled thereby;

10 Fig. 2 is a vertical sectional view showing details of the dobby of Fig. 1;

Fig. 3 is a view similar to Fig. 2 showing details of another form of the new dobby;

15 Fig. 4 is a view in perspective of a chain for use with the dobby;

Fig. 5 is a vertical sectional view showing details of Fig. 3 on an enlarged scale; and

Fig. 6 is a sectional view on the line 6—6 of Fig. 5.

20 The dobby shown in Fig. 1 includes spaced side frame members 10 connected by a rod 11 lying within the forked lower ends of a plurality of harness levers 12. The upper end of each lever is notched to receive a wire loop 13 connected by a wire 14 to the ends of straps 15 passing over sheaves 16 mounted on the loom arch 17. The straps are attached to a harness frame 18 near opposite ends thereof and the frame is connected by straps 19 to the upper ends of springs 20 secured at their lower ends to the floor. Only one harness lever and one harness frame are shown, but the ordinary loom may include fifteen or more harnesses, each connected as described to its own harness lever, the levers lying side by side and engaging the rod 11.

25 Each harness lever is connected near its lower end by an arm 12a to the central pivot of a jack 21, to the opposite ends of which are pivotally attached hooks 22, 23. The upper hook 22 is formed with its hooked end pointing up, while the hooked end of the lower hook 23 points down. The hooks lie between and are engageable with upper and lower knives 24, 25, which extend between the frame members 10 of the dobby with their ends entering slots 10a in the members. The ends of the knives are connected, respectively, by rods 24a, 25a to the opposite ends of rocker levers 26 pivoted on the dobby frame members 10, and the levers 26 are provided with arms 30 26a attached to connecting rods 27 actuated by the usual cranks on a crank shaft of the construction ordinarily used with dobbies. In the operation of the loom, the rockers 26 are rocked once per pick and, as one knife moves out, or 35 away from the loom, the other knife moves in.

Each dobby jack 21 is engageable at its opposite ends with upper and lower girts 28, 29 connecting the dobby frame members and, in this position of a jack, the harness lever connected thereto is held in its extreme inward position by the weight of its harness and the action of springs 20 and the harness is down. The hooks 22, 23 attached to a jack are selectively engageable with their associated knives to effect the raising and lowering of the harness controlled by the jack and the operation of the hooks is controlled as follows.

A plurality of fingers 30, one for each jack, are pivotally mounted on a rod 30x extending between the dobby frame members 10, and each finger is weighted at one end, so that, as seen in Fig. 1, the fingers tend to swing clockwise. The unweighted end of each finger is formed of two parts, of which the part 30a is turned at an angle and is engageable with the under side of the lower hook 23 of the jack controlled by the finger. The other part 30b of the unweighted end of the finger supports one end of a needle 31 movable vertically in upper and lower guides attached to the dobby frame members, and the upper end of the needle is engageable with the under side of the upper hook 22 of the jack controlled by the finger. When the finger is in the position shown in Fig. 1, the upper hook 22 lies with its hooked end out of the path of the upper knife 24, while the lower hook 23 is in such position that its hooked end is in the path of the lower knife 25.

A pattern chain 32 made up of bars 33, each having as many holes 33a as there are fingers 30, is trained over a cylinder 34 mounted on a shaft 34a rotatable in bearings carried by the dobby frame. In an ordinary dobby, the cylinder shaft is driven stepwise to advance the chain by one bar for each pick, but, with the new dobby, the cylinder is driven to advance the chain one bar for each three picks. The chain is prepared by insertion of pegs 35 in holes 33a in bars 33 and, as each bar arrives at the top of the cylinder, the pegs thereon engage the fingers 30 aligned with the pegs and swing the fingers counterclockwise. If a bar in operative position at the top of the cylinder contains no peg opposite a finger, the finger remains at rest and the lower hook 23 controlled by the finger thus lies out of the path of knife 25, while the associated upper hook 22 lies in position to be engaged by the upper knife 24.

In the use of a loom equipped with the new dobby in weaving a reversible center name terry fabric, in which, for example, red lettering appears on the face of the fabric on a white background, the pile warp yarns are drawn in pairs of harnesses, with the red yarns in the No. 1 harness of a pair and the white yarns in the No. 2 harness. This arrangement is used for all the harnesses required for shedding the warp yarns employed throughout the width of the center stripe. In the weaving of a part of the stripe, on which a letter appears, the odd numbered harnesses of the group used for weaving the stripe are raised on the first and third picks of the group of three, which are beaten up simultaneously, and are lowered on the second pick. The corresponding even numbered harnesses of the group are lowered on the first and third picks of each beat-up and raised on the second pick. With these operations, the red yarns form the loops in the lettering on the face of the fabric and the background on the back, while the white yarns form the loops in the back-

ground on the face and the lettering on the back. With the new dobby, only a single bar on the pattern chain is required for each cycle of three picks.

The operation of the dobby may be understood from an examination of Fig. 2, showing how a single odd numbered harness is controlled. As illustrated, the dobby jack 21 is in the in or back position against girts 28, 29 and its harness lever is back and the harness is down. The lower knife is back and the upper knife forward and the chain bar 33 in active position has a pin 35, which has raised the weighted end of the dobby finger 30. As a result, the lower hook 23 has been lowered, so that its hooked end lies in the path of the lower knife 25, while the upper hook lies below the path of travel of the upper knife 24. When the lower knife advances on the first pick of the beat-up, the knife engages and advances the lower hook and this causes the jack 21 to rock on the upper girt 28 as a fulcrum and to pull on the harness lever 12 and raise the harness. On the advance of the lower knife, the upper knife 24 moves back. On the second pick, the bar 33 on the chain remains in position, so that, as the lower knife moves back and the upper knife advances, the jack 21 rocks back to engage both girts, the upper knife missing the upper hook as the knife advances. The operation on the third pick is the same as that on the first, so that, on this beat-up, the harness has been up on the first and third picks and down on the second. At the end of the cycle, the lower hook is engaged with the lower knife in the forward position and the harness is up. At this point, the chain advances by one bar and, if the cycle is to be the same as the first, the bar has no peg in position to engage finger 30.

When the finger 30 is released, the weight on one end swings the finger clockwise, this movement being permitted because the end portion 30a of the finger lies opposite the upwardly curved under surface 23a of the lower hook 23 and is out of contact therewith. As the finger swings, its end portion 30b acts through needle 31 to raise upper hook 22 and place its hooked end in the path of the upper knife 24, then in the back position. When the upper hook advances and the lower hook moves back on the fourth pick, both hooks are engaged by the knives, so that the harness remains up. When the lower knife is fully back, the end portion 30a of the finger frees the lower hook from the lower knife and, for the fifth and sixth picks, the same chain bar stays in place, the lower hook is out of action, and the upper knife and hook cooperate to lower the harness on the fifth pick and raise it on the sixth pick. Thus, in two cycles, the harness is up on the first, third, fourth, and sixth picks and down on the second and fifth picks, so that the cycles are the same. In the first cycle, the lower hook and knife are effective, while, in the second, the upper hook and knife are in operation.

If the pattern requires that the second cycle be the opposite of the first, the second chain bar becoming active will have a peg opposite finger 30. On the fourth pick, the upper knife remains out of operation, and, as the lower knife moves back, the harness is lowered. The lower knife then raises the harness on the fifth pick and lowers it on the sixth. As a result, the harness positions during the second cycle are down, up, down, which is the reverse of the first cycle, namely, up, down, up.

The even numbered harnesses are operated in

the same manner as the odd numbered harnesses but in reverse order. Thus, when the odd numbered harnesses are up, the even numbered harnesses are down. Accordingly, when a given chain bar carries pegs for operation of the fingers controlling the harnesses of one set, the bar has no pegs in position to act on the fingers controlling the harnesses of the other set.

In the dobby illustrated in Figs. 1 and 2, the lower hooks are similar to those in an ordinary dobby, while the upper hooks have been turned upside down, so that their hooked ends point up, and the shanks of the hooks are somewhat straightened out. Also, both hooks are pivoted on pivots lying between the paths of travel of the knives. In the modified construction shown in Fig. 3, each jack 21' is connected to upper and lower hooks 22' and 23', which are of conventional construction and mounted with their hooked ends pointed down. Both hooks are pivoted on pivots lying above the paths of their respective knives. The finger 30' functions as before to raise and lower the lower hook 23' under the control of bars 33' on a pattern chain, and a modified needle is employed to transmit the movements of the finger to the upper hook 22'.

The modified needle comprises a lower section 31a vertically movable in a guide and engaged at its lower end by the end portion 30b' of the finger, and a lever 36 pivoted between its ends on cross-rod 37 and having one end connected to the upper end of needle section 31a. The other end of lever 36 is connected to the lower end of a second needle section 31b vertically movable in a guide and having its upper end in position to engage the upper hook 22' from beneath. A spring 38 wound about rod 37 has one end entering a hole in rod 37 and its other end enters a hole in lever 36. The spring tends to rock lever 36 counter-clockwise, as shown in Figs. 3 and 5, to cause needle section 31b to raise the upper knife 22'.

In the operation of the modified dobby of Fig. 3, a single finger 30' operates both hooks connected to the same jack and, when no peg on the active chain bar engages the finger, the finger swings to raise lower hook 23' out of the path of knife 25' and acts through the compound needle to permit hook 22' to drop down into the path of knife 24'. If the finger is swung by a peg on the chain bar, the lower hook is permitted to swing down to be engaged by knife 25', while spring 38 rocks lever 36 and causes needle section 31b to raise hook 22' out of action. Thus, as in the construction shown in Figs. 1 and 2, a single finger operates both hooks attached to a single jack, causing the hooks to be alternately effective. Accordingly, in the weaving of terry fabrics with the modified dobby, a single pattern chain bar serves to control the three picks in each cycle and, if successive cycles are to be the same, the bar for the first cycle differs from that of the second, in that one has a peg for a given finger and the other is blank.

I claim:

1. In a dobby mechanism, the combination of a plurality of harness levers mounted vertically for pivoting on a horizontal axis and connected to respective harnesses, a plurality of vertical dobby jacks, one for each lever and pivotally connected thereto between its ends, upper and lower girts engageable by the ends of the jacks to limit their movement in one direction, a hook attached to each end of each jack and extending substantially horizontally therefrom, a pair

of knives reciprocable in upper and lower horizontal planes adjacent the hooks, means for reciprocating the knives with the knives moving in opposite directions during each movement of the knives, a pivoted finger for each pair of hooks attached to a single jack, the finger engaging one hook of its pair and being operable to move said hook into and out of the path of one of said knives, needle means actuated by each finger for moving the other hook of its pair into and out of the path of the other knife, and pattern means for operating the fingers, each finger and its needle means co-operating on each operation of the finger by the pattern means to move one hook of the pair controlled by the finger into the path of one knife and to move the other hook of said pair out of the path of the other knife.

2. In a dobby mechanism, the combination of a plurality of harness levers mounted vertically for pivoting on a horizontal axis and connected to respective harnesses, a plurality of vertical dobby jacks, one for each lever and pivotally connected thereto between its ends, upper and lower girts engageable by the ends of the jacks to limit their movement in one direction, a hook attached to each end of each jack and extending substantially horizontally therefrom, a pair of knives reciprocable in upper and lower horizontal planes adjacent the hooks, means for reciprocating the knives with the knives moving in opposite directions during each movement of the knives, a pivoted finger for each pair of hooks attached to a single jack, the finger engaging one hook of its pair and being operable to move said hook into and out of the path of one of said knives, a needle member actuated by each finger, a second needle member engaging the second hook of the pair associated with the finger, a connection between the needle members, the finger acting through the members and connection to move the second hook into and out of the path of the other knife, and pattern means for operating the fingers, each finger and its needle members and connection co-operating on each operation of the finger by the pattern means to move one hook of the pair controlled by the finger into the path of one knife and to move the other hook of said pair out of the path of the other knife.

3. In a dobby mechanism, the combination of a plurality of harness levers mounted vertically for pivoting on a horizontal axis and connected to respective harnesses, a plurality of vertical dobby jacks, one for each lever and pivotally connected thereto between its ends, upper and lower girts engageable by the ends of the jacks to limit their movement in one direction, a hook attached to each end of each jack and extending substantially horizontally therefrom, a pair of knives reciprocable in upper and lower horizontal planes adjacent the hooks, the upper hooks lying below and the lower hooks above the upper and lower knives, respectively, means for reciprocating the knives with the knives moving in opposite directions during each movement of the knives, a pivoted finger for each pair of hooks attached to a single jack, the finger engaging the lower hook of its pair and being operable to move said hook into and out of the path of the lower knife, a needle actuated by the finger for moving the upper hook of its pair into and out of the path of the upper knife, and pattern means for operating the fingers, each finger and its needle co-operating on each operation of the finger by the

pattern means to move one hook of the pair controlled by the finger into the path of one knife and to move the other hook of the pair out of the path of the other knife.

4. In a dobby mechanism, the combination of a plurality of harness levers mounted vertically for pivoting on a horizontal axis and connected to respective harnesses, a plurality of vertical dobby jacks, one for each lever and pivotally connected thereto between its ends, upper and lower girts engageable by the ends of the jacks to limit their movement in one direction, a hook attached to each end of each jack and extending substantially horizontally therefrom, a pair of knives reciprocable in upper and lower horizontal planes adjacent the hooks, the upper hook being pivoted below the path of travel of the upper knife and having its hooked end pointing up and the lower hook being pivoted above the path of travel of the lower knife and having its hooked end pointing down, means for reciprocating the knives with the knives moving in opposite directions during each movement thereof, a pivoted finger for each pair of hooks attached to a single jack, the finger engaging the lower hook of its pair and being operable to move said hook into and out of the path of the lower knife, a needle member actuated by each finger, a second needle member engaging the second hook of the pair associated with the finger, a connection between the needle members, the finger acting through the members and connection to move the second hook into and out of the path of the upper knife, and pattern means for operating the fingers, each finger and its needle members and connection co-operating on each operation of the finger by the pattern means to move one hook of the pair controlled by the finger into the path of one knife and the other hook of said pair out of the path of the other knife.

5. In a dobby mechanism, the combination of a plurality of harness levers mounted vertically for pivoting on a horizontal axis and connected to respective harnesses, a plurality of vertical dobby jacks, one for each lever and pivotally con-

nected thereto between its ends, upper and lower girts engageable by the ends of the jacks to limit their movement in one direction, a hook attached to each end of each jack and extending substantially horizontally therefrom, a pair of knives reciprocable in upper and lower horizontal planes adjacent the hooks, the upper hook being pivoted below the path of travel of the upper knife and having its hooked end pointing up and the lower hook being pivoted above the path of travel of the lower knife and having its hooked end pointing down, means for reciprocating the knives with the knives moving in opposite directions during each movement of the knives, a pivoted finger for each pair of hooks attached to a single jack, the finger engaging the lower hook of its pair and being operable to move said hook into and out of the path of the lower knife, a needle engaged by each finger and engaging the upper hook of the pair associated with said finger, the needle being operable to move said upper hook into and out of the path of the upper knife and pattern means for operating the fingers, each finger and its needle co-operating on each operation of the finger by the pattern means to move one hook of the pair controlled by the finger into the path of one knife and the other hook of said pair out of the path of the other knife.
